UNITED STATES PATENT OFFICE

IRVING J. COX AND WILLIAM E. KIRST, OF WOODBURY, NEW JERSEY, AND CLIFFORD A. WOODBURY, OF MEDIA, PENNSYLVANIA, ASSIGNORS TO E. I. DU PONT DE NEMOURS & COMPANY, OF WILMINGTON, DELAWARE, A CORPORATION OF DELAWARE

PROCESS OF CONCENTRATING NITRIC ACID

Application filed September 15, 1928. Serial No. 306,164.

This invention relates to the concentration of nitric acid to a high strength by means of a dehydrating agent, and more particularly to a method of nitric acid concentration wherein the heat of dilution of the dehydrating agent is utilized and the amount of artificial heat required is reduced to a minimum.

In order to concentrate nitric acid to at least 90% from lower strengths, say from 10 50% to 70% HNO_3 , it is well known in the art that to economically carry out such a process it is necessary to mix the nitric acid with a dehydrating agent and then apply 15 heat which distills out the nitric acid while the water is retained by the dehydrating agent.

It is common practice to mix sulphuric acid with nitric acid and place the mixture 20 in a retort and distill out the nitric acid by means of heat. The first portion of the acid which distills is strong, that is above 85%, and as the distillation proceeds the distillate becomes weaker until the last portions are 25 no stronger than the nitric acid which was originally used. In order to segregate the strong acid a cut-off is generally taken, whereby the weaker cut is returned to the process 30 for concentration. This process is a batch operation and, to overcome the intermittent operation and the repairs to the cast iron retorts used in distillation, a continuous process was proposed by Pauling, U. S. Patent 1,031,864. In the Pauling process dilute nitric acid and strong sulphuric are run down 35 a packed column in admixture or separately but concurrently, while steam is blown into the bottom of the tower, ascending counter-current to the liquid acid mixture, and condenses in it and distills out the nitric acid which leaves the top of the tower as vapors of highly concentrated nitric acid. Various modifications have been proposed by the 40 same inventor but in every case the heating medium is steam, which condenses in the acid mixture.

Steam, when used in this manner, possesses a decided disadvantage in that the water resulting from its condensation dilutes the sulphuric acid used in the process and must

be boiled out of the sulphuric acid before the acid can be used again.

This invention has as an object the concentration of nitric acid to a high strength by the utilization of the heat of dilution of a dehydrating agent with the nitric acid, thus minimizing the amount of steam or other source of heat required, and furthermore minimizing the dilution of the sulphuric acid by the condensation of steam.

A further object of our invention is a process which may be run in direct combination with a sulphuric acid concentration unit, wherein the hot sulphuric acid produced therein may be utilized without cooling and losing the heat as is the common practice in acid manufacture.

A still further object of the invention, when operated in conjunction with a sulphuric acid concentrator, is the return of the hot denitrated acid to the sulphuric acid concentrator as a hot feed, thereby reducing the fuel consumption for concentration about 25% and increasing the capacity of the sulphuric acid concentrating unit.

Other objects will appear as the description proceeds.

These objects are accomplished by the following invention which not only utilizes the heat of dilution of the sulphuric acid but permits the introduction of both acids into the process at a higher temperature than is practical with known existing processes. According to one embodiment of our invention the hot dehydrating agent may be added to either hot or cold nitric acid. This may be carried out either by placing the nitric acid in a still and then adding the dehydrating agent, or preferably by running the two liquids into the top of a packed column. This invention also contemplates preheating both the dehydrating agent and the nitric acid. If a packed column is employed and the liquid allowed to flow through this column, a counter-current of air is used to conduct the vapors up the tower. The vapors of strong nitric acid emerge from the top or near the top of the tower, pass through a bleacher, and are condensed and delivered to a suitable receiver. The hot liquid acid mixture accumu-

lating at the bottom of the dehydrating tower may be run directly to a denitrating tower of the conventional type in which steam is introduced into the bottom in sufficient quantity to denitrate the mixture. The nitric acid vapors forming in the denitrating tower may also be led to a bleacher and condenser.

By reason of the high temperature of the sulphuric acid, it would be expected that the nitric acid would decompose and large amounts of oxides of nitrogen would be produced, but this is not the case. On the contrary, only extremely small quantities of oxides of nitrogen are produced and these may be recovered together with any entrained nitric acid, which is not caught in the condensers, by connecting the condensers to a suitably packed absorption tower.

Without restricting it thereto, we describe the invention with particular reference to the apparatus illustrated in the accompanying drawing, and embodying it as it relates to this apparatus. The drawing shows a diagrammatic side elevation of one assembly of the apparatus suitable for carrying out our process. The dehydrating tower, 1, is constructed of acid-proof material and is packed with some suitable acid-proof packing. The denitrating tower, 2, is of a construction similar to the dehydrating tower. Bleachers, 3 and 4, are constructed of acid-proof material and are packed with acid-proof packing. The condensers, 5 and 6, condense the vapors of each of the towers. The nitric acid is fed to the dehydrating column at 7 and may be preheated if so desired. The sulphuric acid may be introduced into the dehydrating tower and may be fed direct from the sulphuric concentrating unit, or may be otherwise preheated or may be added without heating. Air may be introduced into the dehydrating tower at 9. Steam is introduced into the bottom of the denitrating column at 10. The residual sulphuric acid which contains a small amount of nitric acid is permitted to flow from the dehydrating tower at 11 directly into the denitrating column. The denitrated sulphuric acid flows from the denitrating column at 12. The strong nitric acid produced may be taken from the apparatus at 13 and weak nitric acid, which may be used as such or which may be delivered to the feed of the dehydrating tower, is taken from the apparatus at 14.

When operating the apparatus as described in the foregoing, at least 90% of the nitric acid is obtained as strong nitric acid containing at least 94% acidity. The residual sulphuric acid leaving the denitrating tower will be approximately 78% strength so that the amount of 100% sulphuric acid required as 93% to 95% strength to concentrate one pound of 100% nitric acid of 62% strength will be approximately 3.25 pounds.

Although we have stated that the dehydrat-

ing liquid may be introduced cold it is preferable that both the dehydrating material and the nitric acid enter the dehydrating column at as near their boiling points as practicable.

If the sulphuric acid strength is 90% and the nitric acid 50%, the sulphuric ratio would be about 6.00. If the sulphuric strength is 95% and the nitric 66% the ratio would be about 2.76 parts 100% sulphuric acid per 75 pound 100% nitric acid.

When the residue leaving the dehydrating column is run through the denitrating column counter-current to steam the strength nitric acid obtained is over 50% when no nitric is present in the effluent from this denitrating tower.

While we have described only one embodiment of our process as applied to a continuous tower operation it is within the scope of the invention to carry it out as a batch process in a pot, although a continuous process is preferable from the standpoint of economy and ease of operation. It will be understood from the foregoing that it is possible to use the weak nitric acid from the denitrating column as feed for the dehydrating column or this acid may be taken from the apparatus as weak acid.

As many apparently widely different embodiments of this invention may be made without departing from the spirit thereof, we do not intend to be limited to the herein specific embodiments except as indicated in the appended claims.

We claim:

1. The process of producing highly concentrated nitric acid which comprises adding from 2.7 to 6.0 parts of 100% sulphuric acid of at least 90% strength, and at a temperature of at least 200° C. to about one part of 100% nitric acid of at least 50% strength so as to utilize the heat of the reaction to distill HNO_3 vapors and condensing the strong distillate.

2. The process of producing highly concentrated nitric acid which comprises mixing a dehydrating agent near its boiling point with weak nitric acid so as to utilize the heat of the reaction, and passing the mixture through a tower counter-current to a gaseous medium inert to both acids.

3. The process of claim 2 in which the nitric acid is near its boiling point.

4. The process of claim 2 in which the gaseous medium is air.

5. The process of claim 2 in which the dehydrating agent is sulphuric acid.

6. The process of claim 2 in which the dehydrating agent is sulphuric acid and the gaseous medium is air.

7. The process of producing highly concentrated nitric acid which comprises mixing sulphuric acid near its boiling point with weak nitric acid near its boiling point, main-

taining the boiling temperature by the heat of the reaction and passing the mixture through a tower counter-current to a stream of air.

5 8. The process of producing highly concentrated nitric acid which comprises mixing a dehydrating agent near its boiling point with weak nitric acid near its boiling point, passing this mixture through a tower counter-current to a gaseous medium inert to both acids, recovering the residual hot dehydrating agent and subjecting it to a denitration with a minimum of steam, and adding the resulting condensed vapors to the dehydrating agent as it enters the tower in a continuous cycle.

9. The process of claim 8 in which the dehydrating agent is sulphuric acid.

10. The process of producing highly concentrated nitric acid which comprises introducing into a packed tower from 2.7 to 6.0 parts of sulphuric acid of 90 to 95% strength, maintained at a temperature above 200° C., with one part of nitric acid of 50% to 66% strength, at a temperature above 20° C. so as to utilize the heat of the reaction to distill HNO₃ vapors, recovering in the condensate over 90% of the nitric acid introduced as 94% or higher strength, passing the residual dehydrating agent through a tower counter-current to steam, and obtaining the remainder of the nitric acid as a condensate above 50% strength, with a denitrated residual of about 75% sulphuric acid.

35 In testimony whereof we affix our signatures.
